UNITED STATES PATENT OFFICE.

PAUL SEWERYN, OF NEW YORK, N. Y.

LOCK.

Application filed January 17, 1921. Serial No. 437,787.

To all whom it may concern:

Be it known that I, PAUL SEWERYN, a citizen of Poland, residing at New York, in the county and State of New York, have 5 invented certain new and useful Improvements in Locks, of which the following is a full, clear, and exact specification.

This invention relates to door locks, and has for one of its objects to provide an im- 10 proved lock in which the bolt may be actuated by different cylinder locks on opposite sides of the door.

Other objects will appear as the descrip- 15 tion proceeds.

15 The invention will be first hereinafter described in connection with the accompanying drawings which constitute part of this specification, and then more specifically defined in the claim at the end of the descrip- 20 tion.

In the accompanying drawings, wherein similar reference characters are used to designate corresponding parts throughout the several views:—

25 Figure 1 is an inside elevation of a lock constructed substantially in accordance with this invention and applied to a door which is shown in closed position.

Figure 2 is an outside elevation of the 30 same.

Figure 3 is an elevation of the lock alone, as it appears when removed from the door, looking at the inner face of said lock which engages the inner face of the door when 35 attached.

Figure 4 is a horizontal sectional view through the door jamb, as shown in Figure 1, the keeper and part of the lock being in section.

40 Figure 5 is an edge view of the keeper and jamb to which it is secured.

Figure 6 is an edge view of the lock with the door to which it is attached.

Figure 7 is a detailed view of the lock 45 looking at the same as in Figure 3 but with the inner plate thereof removed.

Figure 8 is a central horizontal section of the lock taken longitudinally of Figure 7.

Figure 9 is a detailed view of the rotary 50 bolt, and

Figure 10 is a left hand end elevation of the lock, as shown in Figure 8, with the end of the casing broken away.

In Figures 1 to 4 inclusive, 1 designates 55 the marginal portion of a door and 2 a part

of a door jamb. A lock casing 3 is secured to the door 1 by means of a projecting plate 7 formed integral with the inner plate 16 of said casing and extending inward along the edge of the door to which it is fastened by 60 any suitable number of screws 9 and 10. The middle screw 9, as best shown in Figures 4 and 6, also engages an inwardly extending lug 8 preferably formed integral with the inner plate 16 and extending into a cavity 65 at one side of the bore 13 in which the outer cylinder lock 12 is housed. This screw 9 is alone sufficient to hold the lock casing to the door, and the other screws 10 shown in Figures 4 and 6 may be omitted. It will be 70 noted that the screw 9 is entirely concealed when the door is closed, see Figure 4, so that when the bolt 19 is engaged with the keeper 4, as illustrated in this figure, it will be im- 75 possible for an unauthorized person to obtain access to said screw for removing the lock from the door.

The keeper 4 is made in the form of a projecting loop on a plate 5 which is secured to the jamb 2 by screws 6. It will be noted 80 that the lock casing is adapted to overlap the keeper, as shown in Figures 1 and 4, so as to not only cover the keeper but also conceal some of the screws 6 which fasten said keeper to the jamb. It is, therefore, im- 85 possible to remove all of the screws which hold the keeper to the jamb when the lock is fastened. As illustrated, three screws are used for fastening the keeper to the jamb and two of said screws are covered by the 90 lock casing when the lock is fastened.

The casing 3 has a cylindrical protruding portion 11 in which a cylinder lock 50 is secured by bolts 41. The cylinder lock 12 is secured to the inner plate 16 of the lock cas- 95 ing by bolts 37 fixed to the plate 16 and ex- tending through lugs 36 on said lock 12 so as to be in alignment with the cylindrical lock 50 when said plate 16 is in place. Nuts 38 are fitted on said bolts 37 at opposite sides 100 of the lugs 36 for adjusting the cylinder lock 12 to fit doors of different thicknesses.

A roll back 33 is secured to the lock 50 by screws 40, Figure 7, and a roll back 34 is swiveled in the plate 16 for actuation by a 105 connecting bar 35 from the cylinder lock 12. Both roll backs 33 and 34 are adapted to be rotated so as to engage a lug 31 on a tumbler 28 which is pivoted to a bolt-actuating slide 24 at 27 and has a locking lug 110

29 yieldingly pressed into engagement with a stop 30 in the casing by a spring 32. The slide 24 has a rack 23 meshing with a segmental gear 22 formed on the hub of a rotary bolt member 18 having an arcuate bolt 19, the end of which is spaced from the opposite face 21 of said bolt member a distance greater than the length of the looped keeper 4. The slide 24 is guided in the casing 3 by lugs 25 projecting from said casing into notches 51 in the slide. The lug 31 on the tumbler 28 extends between a pair of beveled lugs 26 on the slide 24. These beveled lugs are arranged in the path of rotation of the ends of the roll backs 33 and 34, so that after the lug 31 is engaged by either of said roll backs and the tumbler 28 moved thereby to release the lug 29 from the stop 30, said roll back will engage one or the other of the beveled lugs 26 to move the slide 24 in one direction or the other for rotating the bolt 19 into locked or unlocked position.

10 The cylinder locks 12 and 50 are preferably key actuated but the keys for operating them are different, so that when the lock is

15 fastened from one side or the other, it will take a duplicate of the locking key to unlock the door from the same side. Thus, if the door is locked from the inside, an unauthorized person cannot unlock it with a key 30 which fits the outside lock.

20 I claim:—

25 The combination with a lock casing, of a bolt therein, separate key-actuated cylinder locks to be arranged on opposite faces of a 35 door, one of said locks being mounted in the casing and the other connected to said casing but spaced therefrom, a slide operatively connected to said bolt, a tumbler carried by said slide, roll backs corresponding 40 to said locks and mounted in the casing so that either of them may actuate said tumbler, one of said roll backs being directly connected to the lock which is mounted in the casing and a connecting bar extending 45 between the other roll back and the lock which is spaced from the casing.

30 In testimony whereof I have signed my name to this specification.

PAUL SEWERYN.
